UNITED STATES PATENT OFFICE

2,646,883

MAGNETIC SEPARATOR WITH STATIONARY MAGNET

Desmond Walter Molins, Felix Frederic Ruau,
 Valentine Pearce Harvey, and Sydney Alfred
 Nichols, Deptford, London, England, assignors
 to Molins Machine Company, London, England,
 a British company

Application July 12, 1949, Serial No. 104,234
 In Great Britain July 27, 1948

6 Claims. (Cl. 209—223)

1

This invention concerns improvements in or relating to magnetic separators and more particularly separators for removing a relatively small quantity of paramagnetic material from a large mass of other material. An example of such a separator is the magnet system used in cigarette making machines for removing particles of iron, nails, screws and the like from the tobacco as it passes along on a conveyor, such as a carded roller. In time, some quantity of iron is collected on the magnets and it is necessary to remove this and hitherto this has been done by shifting the magnets from their operative position and wiping them. This is an awkward operation and may involve stopping the machine for the sake of safety.

According to the present invention there is provided a separator of the kind referred to comprising a shield or facing of non-magnetic material covering the magnets during the separating operation, means for moving the magnets and shield, to a non-operative position and means for thereafter removing the shield out of the magnetic field whereby paramagnetic material adhering to the shield falls away therefrom. A trough or the like may be positioned beneath the shield to receive the discarded material.

The trough may be coupled to the device for moving the magnets so that the trough moves into and out of the receiving position as the magnets are moved, or the trough may be moved by a separate device and coupled to the shield whereby the trough movement serves to move the shield away from the magnets.

Two ways of carrying the invention into effect will be described with reference to the accompanying drawings which show its application to the tobacco hopper of a cigarette-making machine.

In the drawings:

Figure 1 is a front elevation (shown broken) of the device installed in the hopper.

Figure 2 is a side elevation of Figure 1 in the direction of arrow A with the hopper side at the end adjacent the arrow shown in chain lines.

Figure 3 is a section of part of a tobacco hopper showing a modified form of the invention.

Figure 4 is a view of part of Figure 3 looking in the direction of the arrow B.

Like references refer to like parts in all four figures.

Referring to Figures 1 and 2 of the drawing, a row of permanent magnets 1 are positioned above and along the periphery of a roller 2 (which is omitted from Figure 1) and which conveys the tobacco. The roller is carded but the carding is

omitted in Figure 2 and the roller is identical with that shown in Figure 3.

The magnets are so disposed that the faces of their poles are normal to a radius of the roller 5 and the magnets are supported on a rod 3 journaled in bearings 4 on the side frames 5 of the hopper so that by rotating the rod the magnets can be moved to a non-operative position. A shield 6 of non-magnetic material is attached to the magnets and is of L section, one arm of the L 10 lying close to the poles and the other arm extending along one side of the magnets. The end of the second arm of the L is pivoted at 7 so that the shield can be swung about the pivot against the action of springs 21 and away from the magnets. A pin or abutment 8 is fixed at each end of the shield near the angle of the L so that pressure on said pins will rotate the shield on its pivots and swing the shield away from the magnets.

20 A trough 9 is provided and pivoted at 10 so that it can swing from its normal position to a position where it extends beneath the shield 6 and can receive material falling therefrom, and on each end of the trough is a pawl 11 or the like 25 adapted to engage the corresponding pin 8 on the shield and cause the latter to swing away from the magnets.

When the magnets are in the operative position, as shown in Figure 2 paramagnetic material removed from the tobacco on the carded roller 2 30 by the magnets naturally adheres to the face of the shield. When it is desired to clean the shield of such material a lever 12 is moved to the position shown in chain lines in Figure 2 whereby the magnets and the shield are caused to swing 35 around the pivots of the rod 3, and brought to a non-operative position. Another lever 13 is then manipulated to swing the trough about its pivots 10 from its normal position, Figure 2, to the receiving position beneath the shield 6, the latter element being then in the chain line position shown, and during this movement the pawls 11 40 on the trough encounter the pins 8 on the shield 6 and cause the latter to swing on its pivot 7 away from the magnet. The parts are so shaped and timed that the shield moves well within the confines of the trough before the shield is far enough away from the magnets for the paramagnetic material to be sufficiently free of the magnetic field for the material to drop from the shield. 45 In this way all the material is safely caught in the trough and cannot fall back on to the carded roller in which case it might pass into the rod forming apparatus of the machine and cause damage.

55 The free edge of the part of the shield which

lies close to the poles of the magnets is curved or bent outwardly to form a lip 14. The purpose of this is to prevent particles of paramagnetic material from running off the shield on to the magnets under the influence of the magnetic field, while the shield is being swung towards its inoperative position.

While the arrangement described for moving the trough and shield is very convenient, it will be seen that according to the kind of machine 10 in which the separator is employed, it may be desirable to modify the design, and this may be done without departing from the scope of the invention.

The lever 12 is held in the chain line position 15 by a latch 15 pivoted at 16. This latch is released manually when it is desired to return the magnets to the operative position. During the swinging movement of the trough it is guided by pins 17 fixed to the pawls 11 which run in slots 18 formed 20 in quadrants 19 screwed to the hopper walls. A torsion spring 20 holds the trough 9 in the inoperative position. When there is sufficient material in the trough 9 to warrant emptying it, it is lifted off its pivots 10, for as may be seen from Figure 25 2 the part of the trough which engages the pivots is slotted.

It will be seen however, from Figure 1, that the lever 13 is permanently attached to the pivot side by its pivot pin 22. In order therefore, to allow the trough to be removed as stated, a crank 23 is fixed on the inner end of the pin 22 and at the free end thereof is a crank pin 24 which works in an open-ended slot 28 in a plate 29 which is riveted to the end wall of the trough 9.

In an alternative construction shown in Figures 3 and 4 which is designed for use with a different kind of hopper in which there is less room for moving the magnets and associated parts, the magnets are carried on two links 25 and 26, 40 pivoted at 27 and 28 respectively, whereby they can, by a swinging movement of the links, be moved in the direction of the arrow and away from the carded roller to a non-operative position. The reason for this arrangement is that in this hopper it is necessary to arrange for magnets to extend between two small rollers 30 and 31 adjacent the carded roller 2, and it is thus necessary to withdraw the magnets rearwardly to avoid fouling the roller 30 and the parts shown above the roller 31. The links are so arranged that the magnets move almost in a straight line radial to the carded roller. One of the links carries a pawl 32 arranged to engage pin 33 on the non-magnetic shield 6 for the purpose of swinging it away as in the construction previously described. Due to the arrangement of the links the pawl overtakes the pin 33 while the magnets are moving away from the carded roller but does not engage the pin until the magnets are clear of the small rollers. Thus the shield remains in position until the magnets are clear, being held in position by the spring 21. A trough 34 is located in the hopper in a suitable position such that the shield is above the trough by the time it has been swung away from the magnets a sufficient distance for the paramagnetic material adhering to the shield to be free of the magnetic field. The trough in this case is stationary, so far as any automatic operation is concerned and supported on pins 35 fixed to the hopper side, but it is arranged so as to be easily displaceable removable for emptying from time to time. A stop 36 on the lever 26 limits the magnets movement by engagement with the lever 25.

What we claim as our invention and desire to secure by Letters Patent is:

1. In a magnetic separator of the class described, in combination, a supporting frame, at least one separating magnet, a surface moving relative to said magnet and providing a conveyor for material from which extraneous magnetic bodies are to be extracted, displaceable means for securing said magnet to said supporting frame for adjustment to and from a position adjacent said conveyor surface where the passing material is in the field of attraction of said magnet and such bodies are attracted to the magnet and separated from the mass of material, means for displacing said first named means for moving said magnet away from said conveyor surface, a non-magnetic shield distinct and separate from the conveyor surface and covering said magnet during the separating operation whereby said bodies adhere to said shield while it remains in magnet covering position, a displaceable trough carried by said supporting frame, one of the positions of said trough being that in which it is disposed beneath the magnet and shield when the latter members are moved away from the conveyor surface, and means associated with said shield and automatically operable upon abutment with one of the above recited displaceable parts of the separator to remove the shield 30 out of the field of the magnet while the shield is above the trough, whereby any paramagnetic bodies adhering to the shield fall away therefrom.

2. A separator as set forth in claim 1 in which the last named means includes a projection on said shield which is adapted to be contacted by an element associated with and movable simultaneously with said trough.

3. In a magnetic separator of the class described, in combination, a supporting frame, at least one separating magnet, a surface moving relative to said magnet and providing a conveyor for material from which extraneous magnetic bodies are to be extracted, displaceable means for securing said magnet to said supporting frame for adjustment to and from a position adjacent said conveyor surface, upon the opposite side of the mass of material thereon from said surface and so that the passing material is in the field of attraction of said magnet and such bodies are attracted to the magnet and separated from the mass of material, means for displacing said first named means for swinging said magnet away from said conveyor surface, a non-magnetic shield covering said magnet during the separating operation whereby said bodies adhere to said shield while it remains in magnet covering position, a displaceable trough carried by said supporting frame, one of the positions of said trough being that in which it is disposed beneath the magnet and shield when the latter members are swung away from the conveyor surface, and spring means for resiliently and yieldably urging said shield into covering relationship with said magnet, a projection on said shield adapted to abut one of the above recited displaceable parts of the separator to remove the shield out of the field of the magnet while the shield is above the trough, whereby any paramagnetic bodies adhering to the shield fall away therefrom.

4. In a magnetic separator of the class described, in combination, a supporting frame, at least one separating magnet, a surface moving relative to said magnet and providing a conveyor for material from which extraneous magnetic bodies are to be extracted, means for displaceably

securing said magnet to said supporting frame adjacent said conveyor surface and so that the passing material is in the field of attraction of said magnet and such bodies are attracted to the magnet and separated from the mass of material, means for moving said magnet away from said conveyor surface, a non-magnetic shield covering said magnet during the separating operation whereby said bodies adhere to said shield while it remains in magnet covering position, said magnet securing means comprising two side-by-side links having their adjacent remote ends pivoted to the supporting frame at a fixed distance apart and their opposite ends pivotally connected to spaced points on the magnet, thereby providing an approximate parallel-motion linkage support, the said support being thus arranged to swing said magnet approximately in a straight line normal to the conveyor surface.

5. A separator as set forth in claim 4 in which the conveyor surface is that of a cylinder and the path of movement of said magnet is substantially radial thereto.

6. A separator as set forth in claim 4 in which

the link which is leading as the magnets move toward non-operative position provides an abutment adapted to engage the following link toward the end of the movement and arrest the magnet in the desired remote position.
